CONCRETE BUILDING CONSTRUCTION

Herbert Pitman Falls, Vancouver, British Columbia, Canada

Application September 26, 1938, Serial No. 231,815

7 Claims. (Cl. 72—1)

This invention relates to improvements in concrete building construction.

An object of the present invention is the provision of a method of erecting concrete buildings with hollow walls without the necessity of using forms or precast blocks or slabs in said walls.

Another object is the provision of a concrete building construction of greater strength than heretofore with the use of less concrete.

Another object is the provision of a concrete building construction requiring less time and labour and by means of which the cost of materials may be decreased.

A further object is the provision of a monolithic wall construction having improved insulation qualities.

Heretofore, hollow concrete walls have been erected but in most instances it is necessary to erect forms into which the concrete is poured and after the concrete has set, the forms are removed. This entails considerable labour and the form material is wasted. Another outstanding disadvantage of certain constructions is that cores formed, in part at least, of wood are left in the walls in order to provide air spaces. This wood absorbs moisture and, therefore, swells thus tending to deform and crack the wall. This defect is so prominent that it has rendered this method of construction impractical. A further disadvantage lies in the fact that, after a time, the wood decays with dry rot.

The present invention overcomes these objections by providing a concrete building construction wherein forms are unnecessary for the building of the walls and spacers or cores formed of treated corrugated cardboard, are used whereby a plurality of dead air spaces are provided thus increasing considerably the insulation qualities of the wall. These cores are strong enough to retain the concrete in place while the wall is being erected and, at the same time, they will not absorb moisture and swell up to deform the wall. The cores are intended to be left in the wall after it is completed where they act as insulation and they are not subject to dry rot. A variation of this invention is the use of cores or spacers that may be removed for repeated use. In any event, the cost of cores or spacers for any wall is negligible in comparison to the cost in the known methods of construction.

This invention also aims to provide a novel method of assembling floor slabs with the walls, joists, beams and supporting posts, said floor slabs in themselves being improved over the known floor slabs. In this construction, both the

joists and the beams rest upon the supporting posts and the joists are formed to receive the ends of the floor slabs. The edges of the outer slabs of the floor and the ends of the outer beams and joists rest upon the top of the wall so that the slabs form a seal for the air spaces in the wall. Furthermore, a novel method of erecting the outer staircases is provided whereby considerable labour and time is saved.

The present invention is more fully described in the following specification and illustrated in the accompanying drawings, in which

Figure 1 is an enlarged fragmentary sectional view, taken through a wall, showing one form of spacer or core therein,

Figure 2 is a vertical section through a wall of a building,

Figure 3 is a fragmentary plan view of two walls at a corner, showing the position of the floor slabs, beams and joists at this point,

Figure 4 is a perspective view of an alternative form of spacer or core, with certain sections broken away to show the interior thereof,

Figure 5 is a view, partly in section, showing the beams and joists mounted upon the upper end of a supporting post and the floor slabs resting upon the joist,

Figure 6 is an enlarged fragmentary section taken on the line 6—6 of Fig. 3, and

Figure 7 is a side elevation of an outer stair-case, showing the connection to a wall.

Referring more particularly to the drawings, the wall 10 is erected upon a concrete footing 11. This wall is erected in the following manner:

A plurality of spaced-apart spacers or cores 12 are placed on end upon the footing 11 in line with each other. Each core 12 is in the form of a rectangular tube extending substantially the height of a storey of the building and consists of outer and inner layers 13 and 14 of cardboard or similar material between which is disposed a central layer 15 of corrugated cardboard or the like, each of said layers being waterproofed and treated to prevent bacterial decay. If desired, braces 16 formed of wood or other suitable material, may be removably inserted in the cores 12, said braces extending the full length of the cores.

After the cores are set in place, U-shaped rods 17 are placed between the ends of the cores and held in a vertical position while horizontal temperature rods 18 are tied to the vertical arms of said U-rods. The temperature rods extend substantially the full length of the wall along the inside of the arms of the rods 17 and along the

outer surfaces of the cores 12, said arms being disposed beyond each side of the cores. There are a pair of rods 18 extending longitudinally of the wall at approximately the tops of the window openings and another pair at approximately the bottoms of said openings. Layers 20 of wire mesh or netting are tied to the outsides of the vertical arms of the rods 17 and extend substantially the full length and height of the wall on each side of the cores 12. A ground piece 21 is tied to each arm of the rods 17 situated on the inner side of the cores, and strappings 22 are secured thereto, upon which laths or the like are nailed after the wall has been completed.

15 The concrete is applied to the above described framework by means of the well known Gunite machine. The necessary ingredients, such as cement, sand, gravel and water, are mixed in the machine and discharged outwardly under 20 pressure through a nozzle. As the wall is built up, a suitable thickness of concrete is applied to each side of the cores 12 and, at the same time, webs 23 are formed between the ends of adjacent cores. As the wall nears the tops of the cores, 25 suitable forms are placed thereon at desired intervals and preferably on the webs 23, so that, when the wall is level with the cores, openings are formed therein into which the ends of beams 24 may be placed. The outer ends of the beams 30 24 extend only to the outer arms of the rods 17. The removal of the braces 16 completes the first 30 storey wall. The concrete embeds the cores 12, the rods 17 and 18, the wire mesh or netting 20, and the ground pieces 21, but the strappings 22 35 project beyond the inner surface of the concrete.

Precast reinforced supporting posts 25 are placed at suitable positions in relation to the wall 12 on footings 26. The inner ends of the beams 40 24 rest on the upper ends of the posts 25, as clearly illustrated in Fig. 2. Precast joists 27 also rest on the upper ends of the posts 25 between the ends of the beams 24, said joists being recessed to form shoulders 28 upon which floor 45 slabs 30 rest. These floor slabs extend along the beams 24 to the outer ends thereof and abut against the inner vertical arms of the rods 17. It might be added here that the outer ends of the joists 27 extend into the wall 10 in the 50 same manner as the ends of the beams 24. The joists 27 are reinforced by rods 31 extending longitudinally thereof adjacent the tops and bottoms of these rods are joined together by reinforcing straps 33, see Fig. 5.

55 By referring to Fig. 6, it will be seen that the floor slabs 30 are formed with grooves 34 in the edges thereof, into which reinforcing rods 36 project. The upper surfaces of the floor slabs are slightly smaller than the lower surfaces 60 thereof so that there is a space 37 extending upwardly from the grooves 34 when the slabs are brought together.

When the beams, joists and floor slabs are mounted in position, as described, concrete is 65 blown by means of the Gunite machine into the grooves 34 and the spaces 37 between the floor slabs to bind said slabs together. At the same time, concrete is blown into any space there may be between the outer ends of the beams and 70 joists and the walls 10 and, if necessary, concrete may be blown between the edges of the floor slabs resting on the shoulders 28 of the joists and the joists themselves. With this construction, the outer edges of the floor slabs act as a seal over 75 the upper ends of the cores 12.

The next section of the wall 10 is erected upon the floor slabs 30. The outer arms of the rods 17 of the lower wall extend upwardly past the beams 24 and the floor slabs 30 are tied to the outer arms of the rods 17 of the upper section of 5 the wall, as at 40. Reinforcing dowels 41 are tied to the inner arms of the upper rods 17 at 42 and extend downwardly through holes formed in the outer floor slabs 30, into the webs 23 of the lower section of the wall, it being understood that 10 these reinforcing dowels are set in place before the concrete of the lower wall has set. The upper section is then constructed and erected in the same manner as the lower section. When the concrete of the upper wall is being applied, the 15 outer surface thereof is brought down past the edges of the floor slabs to join the outer surface of the lower wall. After the spacers 16 are removed from the cores, the top of the upper wall is sealed by means of a wall plate 43 through 20 which both arms of the rods 17 extend where they are bent, as at 44.

The floor 45 is nailed to straps 46 resting on the floor slabs 30. Laths are nailed to the strappings 22 and plaster is placed on the laths. In 25 this manner a dead air space is formed between the inner surface of the wall 10 and the laths.

A wall constructed in this manner is reinforced vertically and longitudinally by the U-shaped rods 17, the temperature rods 18 and the wire 30 mesh or netting 20. The cores 12 form a plurality of dead air spaces 47. A particular feature of this invention is that a plurality of dead air cells 48 are formed in each core by the outer and inner layers 13 and 14 combined with the central corrugated layer 15 thereof. Another fact to be considered is that there are six layers of 35 cardboard or similar material in each core which serve to increase the insulation qualities of the wall. 40

An alternative form of spacer or core 50 is illustrated in Figure 4, which may be used in climates where insulation is not so essential. The spacer or core 50 formed of waterproofed wood or other material, is rectangular in cross 45 section and tapers downwardly from the top to the bottom thereof. Each core is provided with a top 51 and a bottom 52, each having a ventilation opening 53 therein. A ring 54 is secured to the top 51 and braces 55 extend longitudinally of the 50 core. The cores 50 extend substantially the full height of each section of the wall and they are withdrawn therefrom by means of the rings 54 when the concrete has set, their tapered construction making this possible. These cores may 55 be used repeatedly.

Fig. 7 illustrates the construction of a concrete outer staircase and verandah. Two precast, reinforced side panels 56 spaced apart the desired width of the stairs and verandah, are disposed at right angles to the wall 10. Precast, reinforced wall slabs 57 are secured by bolts 58 to the wall 10 and to the side panels 56, the required distance above the ground, and precast, reinforced stringers 60 are also bolted to said 6 side panels and extend therefrom to the ground. A large precast, reinforced floor slab 61 is placed 65 on the wall slabs 57 and is held in place in any suitable manner, such as by dowels. Precast, reinforced treads 62 and risers 63 placed on the 7 stringers, are also held in position by dowels. This completes the construction, which is very simple and durable.

From the above, it will readily be seen that an improved concrete construction has been pro- 7

vided by means of which hollow walls may be constructed without the use of the customary forms, said walls being durable, easily constructed and having exceptional insulating qualities.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set forth in the accompanying claims.

What I claim as my invention is:

1. In concrete building construction, a wall having therein a plurality of spaced-apart cores in line with each other and extending substantially the height thereof, a plurality of vertical rods disposed beyond each side of the cores and arranged between the ends of adjacent cores, horizontal temperature rods tied to the vertical rods on each side of the cores, said temperature rods extending the full length of the wall inside of the vertical rods and along the outer surfaces of the cores, wire mesh extending on each side of the cores the full height and length of the wall and tied to the vertical rods on the outside thereof, ground pieces tied to the vertical rods situated on the inner side of the cores, strappings secured to the ground pieces upon which laths or the like may be secured, and concrete embedding the cores, rods, wire mesh and ground pieces, said strappings projecting beyond the inner surface of the concrete.

2. In concrete building construction, a wall having therein a plurality of spaced-apart cores in line with each other and extending substantially the height thereof, a plurality of U-shaped rods arranged between the ends of the cores, said rods having vertical arms disposed beyond each side of the cores, horizontal temperature rods tied to the vertical arms above and below the window openings of the wall, said temperature rods extending the full length of the wall inside the vertical arms and along the outer surfaces of the cores, wire mesh extending the full height and length of the wall tied to the vertical arms on the outside thereof on each side of the cores, a ground piece tied to each vertical arm situated on the inner side of the cores, strappings secured to the ground pieces upon which laths or the like may be secured, and concrete embedding the cores, rods, wire mesh and ground pieces, said strappings projecting beyond the inner surface of the concrete.

3. In concrete building construction, a wall having therein a plurality of spaced-apart cores formed of cellular corrugated cardboard or the like, said cores being in line with each other and extending substantially the height of the wall, a plurality of vertical rods disposed beyond each side of the cores and arranged between the ends of adjacent cores, horizontal temperature rods tied to the vertical rods on each side of the cores, said temperature rods extending the full length of the wall inside the vertical rods and along the outer surfaces of the cores, wire mesh extending on each side of the cores the full height and length of the wall and tied to the vertical rods on the outside thereof, ground pieces tied to the vertical rods situated on the inner side of the cores, strappings secured to the ground pieces upon which laths or the like may be secured, and concrete embedding the cores, rods, wire mesh and ground pieces, said strappings projecting beyond the inner surface of the concrete.

4. In concrete building construction, a wall having therein a plurality of spaced-apart, rectangularly shaped cores formed of cellular corrugated cardboard or the like which has been waterproofed and treated to prevent bacterial decay, said cores being in line with each other and extending substantially the height of the wall, a plurality of U-shaped rods arranged between the ends of the cores, said rods having vertical arms disposed beyond each side of the cores, 10 horizontal temperature rods tied to the vertical arms of the rods, said temperature rods extending the full length of the wall inside the vertical arms and along the outer surfaces of the cores, wire mesh extending the full height and length 15 of the wall tied to the vertical arms on the outside thereof, ground pieces tied to the vertical arms situated on the inner side of the cores, strappings secured to the ground pieces upon which laths or the like may be secured, and concrete embedding the cores, rods, wire mesh and ground pieces, said strappings projecting beyond 20 the inner surface of the concrete.

5. In concrete building construction, a wall having therein a plurality of spaced-apart rectangular shaped cores formed of inner and outer layers of cardboard or the like with a central layer of corrugated material forming therein a plurality of dead air cells, said cores being in line with each other and extending substantially the 25 height of the wall, a plurality of vertical rods disposed beyond each side of the cores and arranged between the ends of adjacent cores, horizontal temperature rods tied to the vertical rods on each side of the cores, said temperature rods extending the full length of the wall inside the vertical rods and along the outer surfaces of the cores, wire mesh extending the full height and length of the wall tied to the vertical rods on the outside thereof, ground pieces tied to the vertical rods situated on the inner side of the cores, strappings secured to the ground pieces upon 30 which laths or the like may be secured, and concrete embedding the cores, rods, wire mesh and ground pieces, said strappings projecting beyond 35 the inner surface of the concrete.

6. In concrete building construction, a wall having therein a plurality of spaced-apart cores formed of inner and outer layers of cardboard or the like with a central layer of corrugated material forming therein a plurality of dead air cells, 40 said layers having been waterproofed and treated to prevent bacterial decay, braces removably inserted in the cores adapted to be removed when the wall is completed, said cores being in line with each other and extending substantially the height of the wall, a plurality of U-shaped rods arranged between the ends of the cores, said rods having vertical arms disposed beyond each side of the cores, horizontal temperature rods tied to the vertical arms above and below the window 45 openings of the wall, said temperature rods extending the full length of the wall inside the vertical arms and along the outer surfaces of the cores, wire mesh extending the full height and length of the wall tied to the vertical arms on the outside thereof on each side of the cores, a ground piece tied to each vertical arm situated on the inner side of the cores, strappings secured to the ground pieces upon which laths or the like 50 may be secured, and concrete embedding the cores, rods, wire mesh and ground pieces, said strappings projecting beyond the inner surface of the concrete.

7. In concrete building construction, a wall 55

8. In concrete building construction, a wall 60

9. In concrete building construction, a wall 65

10. In concrete building construction, a wall 70

11. In concrete building construction, a wall 75

- having therein a plurality of spaced-apart, tapered cores formed of wood or the like, each core having a top and bottom with ventilation openings therein and a ring secured to the top by means of which the core may be removed from the wall when the latter is completed, said cores being in line with each other and extending substantially the height of the wall, a plurality of vertical rods disposed beyond each side of the cores and arranged between the ends of adjacent cores, horizontal temperature rods tied to the vertical rods on each side of the cores, said temperature rods extending the full length of the

wall inside the vertical rods and along the outer surfaces of the cores, wire mesh extending on each side of the cores the full height and length of the wall tied to the vertical rods on the outside thereof, ground pieces tied to the vertical rods situated on the inner side of the cores, strappings secured to the ground pieces upon which laths or the like may be secured and concrete embedding the cores, rods, wire mesh and ground pieces, said strappings projecting beyond the inner surface of the concrete.

HERBERT PITMAN FALLS.
